UNITED STATES PATENT OFFICE.

RYUJI SATO, OF NEW YORK, N. Y.

WRITING INSTRUMENT.

Application filed February 12, 1924. Serial No. 692,335.

To all whom it may concern:

Be it known that I, RYUJI SATO, a citizen of Japan, residing at New York city, in the county of New York and State of New York, have invented new and useful Improvements in Writing Instruments, of which the following is a specification.

This invention relates to writing instruments and more particularly to a double fountain pen.

The principal object of the invention is the provision of a writing instrument wherein there is embodied two pens for permitting two different style pen points or nibs for instant use, and which pen points receive their supply of ink from a single reservoir.

Another object of the invention is to provide a double fountain pen which includes suitable caps for protecting the pen nibs when not in use, and for sealing the leakage of ink from the reservoir to the pen when the caps are in position on their respective ends.

A further object of the invention is to provide a double fountain pen having caps for covering the pen nibs, the said caps being capable of telescopic engagement with each other when either pen is being used for writing purposes.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is an elevation of my invention showing one of the caps removed and in telescopic engagement with the other cap.

Figure 2 is a vertical longitudinal sectional view on the line 2—2 of Figure 1.

Figure 3 is a detail sectional view through one of the caps showing the means for sealing the escape of ink from the nib.

Figure 4 is a transverse sectional view on the line 4—4 of Figure 3.

Figure 5 is a transverse sectional view on the line 5—5 of Figure 2.

Figure 6 is a detail view partly in section of the refill member.

Referring more particularly to the drawing, the reference numeral 10 designates my improved writing instrument in its entirety

which includes a casing 11 provided at opposite ends with pen sections 12. Caps 13 close the ends of the pen sections and each cap is reduced at its outer end as at 14 so as to be capable of telescopic engagement with each other when either pen section is uncovered for writing purposes. The tubular member 11 has its ends reduced and externally screw threaded as at 15 for coaction with an internally threaded portion 16 formed on a holder 17, which holder constitutes part of each pen section 12. Each holder 17 is also provided with an annular flange 18 which is spaced from the internally threaded portion 16 and encircles the end of a refill tubular member 19 containing a supply of ink and which member is opened at opposite ends for communication with a duct 20 in each of the holders 17. The other end of each duct opens against a pen nib 21 carried by the holder 17. A shank or extension 22 projects from the holder and supports the pen nib in the usual manner. With reference to Figure 6, it will be seen that stoppers 23 close the refill tubular member 19 prior to its insertion in the casing 11 and the same may be manufactured and sold in this manner, so that a new supply of ink may be placed in the casing when the former supply has been exhausted.

To prevent leakage of ink from the pen sections into the caps 13 when the device is being carried in the pocket, I provide the inner walls of each cap with a pair of yieldable blocks 24 in the nature of a soft rubber or cork, between which the nib 21 and the shank 22 is adapted to be received. When the caps have been applied to close the ends of the pen sections, the nib and shank will be brought into clamping engagement with each other in order to close the duct 20 to prevent the flow of ink to the nib.

From the foregoing description, it will be seen that two different style nibs or pen points may be embodied in a single writing instrument, and which nibs receive their supply of ink from a single reservoir.

While I have described what I deem to be the most desirable embodiment of my invention, it is obvious that many of the details may be varied without in any way departing from the spirit of my invention, and I therefore do not limit myself to the exact details of construction herein set forth.

nor to anything less than the whole of my invention limited only by the appended claims.

What is claimed as new is:—

6. 1. A writing instrument comprising a casing having a pen section at each end thereof, and a single reservoir supported by said sections for supplying ink thereto.
- 10 2. A writing instrument comprising a casing having a pen section at each end thereof, a single removable reservoir supported by said sections for supplying ink thereto, and means for sealing the flow of ink to said sections when not in use.

3. A writing instrument comprising a casing, a pen section attached to said casing at opposite ends thereof, a tubular member containing a charge of ink insertable in said casing and supported therein by said pen sections, a pen nib carried by each of 20 said pen sections, and a bore in each pen section communicating with said tubular member and said pen nib for supplying ink thereto.

In testimony whereof I have affixed my signature.

RYUJI SATO.
